UNITED STATES PATENT OFFICE.

JULIAN KENNEDY, OF PITTSBURGH, PENNSYLVANIA.

GAS-DRIER.

1,280,043.

Specification of Letters Patent. Patented Sept. 24, 1918.

Application filed April 16, 1918. Serial No. 228,837.

To all whom it may concern:

Be it known that I, JULIAN KENNEDY, residing at Pittsburgh, in the county of Allegheny and State of Pennsylvania, have 5 invented a new and useful Improvement in Gas-Driers, of which the following is a full, clear, and exact description, reference being had to the accompanying drawings, forming part of this specification, in which—

10 Figure 1 is a vertical section of a gas drier embodying my invention;

Fig. 2 is a horizontal section showing a battery of the driers, the section being taken on the plane of the irregular line II—II of 15 Fig. 1;

Fig. 3 is a plan view showing a modification; and

Fig. 4 is a sectional view of a portion of the apparatus shown in Fig. 1.

20 My invention has relation to gas driers, and is more particularly designed for the treatment of blast furnace gases after the same have been cleaned by passing through the usual gas washers.

25 The object of my invention is to provide a simple and efficient form of drier, in which the use of moving parts is obviated and which can be constructed and operated at a relatively small cost.

30 The nature of my invention will be best understood by reference to the accompanying drawings, in which I have shown the preferred embodiment thereof and which will now be described, it being premised, 35 however, that various changes can be made in the details of construction and arrangement of the various parts, without departing from the spirit and scope of my invention as defined in the appended claims.

40 In these drawings, the numeral 2 designates a vertical casing supported at its base in a suitable framing 3. This casing may conveniently consist of sheet metal sections placed end to end and secured together by 45 any suitable external joints, such as the external strips 4, riveted thereto, as shown in Fig. 4. The lower end of the casing is provided with a hopper section 5, having a discharge opening 6 at its bottom, and 50 which may be controlled by a suitable door or gate 7.

Placed centrally within the casing is a vertical post or column 8, preferably hollow. This column is shown as being supported at its lower end in a suitable spider 55 9, secured to the interior wall of the casing

and at its upper end is rigidly connected to a cover plate 10, which is removably secured to the casing head 11. Secured to this central post or column and winding around the 60 same is a helical baffle 12. The gas to be treated enters the upper portion of the casing above the top portion of the baffle, by a suitable inlet connection, such as shown at 13, and the dried gas passes out of the lower portion of the casing by means of the outlet pipe 14. This pipe is preferably extended through one side of the casing at an oblique angle, its lower end terminating centrally within the casing and a short distance 70 above the hopper section 5. This lower end portion is preferably provided with a surrounding flange 15, placed at substantially right angles to the axis of this portion of the pipe and which serves as a deflector for 75 water and flue dust which falls upon the pipe.

In practice, a battery of the driers may be arranged as shown in Fig. 2, the several inlet connections 13 being connected to a common gas supply main (not shown) while the outlet pipes 14 are connected into a common manifold 16.

In order to keep the helical baffles clear of dust and dirt which may be deposited thereon from the gases being treated, I provide each of the driers with a vertical series of water jets 17, these jets extending into the casing through openings 18 at one side thereof.

90 It will be noted that the gas inlets are tangentially arranged, and this, together with the helical arrangement of the baffles 12, produces a whirling movement of the gases around these pipes downwardly 95 through the drier. In this manner, excessive moisture is removed by centrifugal action, together with a considerable percentage of any fine flue dust which may remain in the gases. This combined water 100 and a fine dust is discharged into the hopper section 5, from which it may be removed, as may be desired. By introducing water through the jet pipe 17 at intervals, the baffles may be prevented from becoming 105 clogged.

The baffles 12 may be conveniently formed of sheet metal riveted at their inner edges to the central post or column 8, as indicated at 19 in Fig. 4, and having a reinforcing strip 20, secured to the underside of their outer portions. Preferably all the rivets which

are employed have their heads countersunk in those surfaces with which the gas comes immediately in contact, and this, together with the absence of any internal joints in 5 the casing, prevents all obstructions to the flow of gas through the drier.

By removing the bolts or other fastenings which secure the cover 10 to the casing head 11 and engaging a crane hook with the 10 perforations 21, the central post or column of the baffle can be readily removed from within the casing.

In the modification shown in Fig. 3, such removal is provided for by making the casing 15 in two sections 2^a and 2^b, the section 2^a being hinged to the section 2^b, so that it can be swung open to permit the removal of the column and baffle.

It will be noted that the arrangement of 20 the gas outlet pipe is such that the gas which has passed the helical baffle and escaped into the chamber between the baffle and the hopper portion 5 is caused to make a positive change in the direction of flow in order to 25 enter the outlet pipe. This change in direction of flow acts to cause the precipitation of a considerable percentage of moisture and dirt which may still be contained in the gas.

I claim:—

30 1. A gas drier comprising a vertical casing having a gas inlet at its upper portion, a hopper-shaped lower portion provided with

a dirt and water discharge, a helical baffle extending within said closure and terminating at its lower end at a point above the 35 said hopper portion, and a gas outlet pipe extending obliquely downwardly through one side of the casing at a point between the lower end of the baffle and said hopper-shaped portion and having its open inlet end 40 terminating above said hopper portion, substantially as described.

2. A gas drier comprising a vertical casing having a gas inlet at its upper portion, a hopper-shaped lower portion provided with a dirt and water discharge, a helical baffle extending within said closure and terminating at its lower end at a point above the 45 said hopper portion, and a gas outlet pipe extending obliquely downwardly through one side of the casing at a point between the lower end of the baffle and said hopper-shaped portion and having its open inlet end 50 terminating above said hopper portion, substantially as described.

In testimony whereof, I have hereunto set my hand.

JULIAN KENNEDY.
